UNITED STATES PATENT OFFICE.

CHARLES A. BELKNAP, OF NEW YORK, N. Y., ASSIGNOR OF ONE-HALF TO
CHARLES E. PARSONS, OF SAME PLACE.

ENVELOP OR WRAPPER ADDRESSING MACHINE.

SPECIFICATION forming part of Letters Patent No. 643,894, dated February 13, 1900.

Application filed April 28, 1899. Serial No. 714,142. (No model.)

To all whom it may concern:

Be it known that I, CHARLES A. BELKNAP, a citizen of the United States, residing at New York, borough of Brooklyn, and State of New York, have invented certain new and useful Improvements in Machines for Addressing Envelops or Wrappers, of which the following is a specification.

Heretofore machines of this class have been very ponderous and large, so that they are hard to handle and difficult to keep in repair; and the main object of my present invention is to make machines of this class as light, small, compact, and simple as possible, consistent with efficiency and the amount of work which is to be handled.

Further objects of my invention are to improve the construction of the means for forwarding the stencil-cards to be inked and also the means for supplying ink for the impression to be made through the cards.

The invention consists of certain features of construction and combinations of parts to be hereinafter described and then claimed.

In the accompanying drawings, Figure 1 is a side elevation of my improved machine for addressing envelops and wrappers. Fig. 2 is a plan view of the machine. Fig. 3 is a detail transverse section on line 3 3 of Fig. 2, showing also the collecting-box. Fig. 4 is a vertical transverse section on line 4 4, Fig. 1. Fig. 5 is a vertical longitudinal section showing the oscillating stencil-carrier lowered just previous to making the impression. In this figure the stencil-cards have not quite reached their forward position. Fig. 6 is also a central longitudinal section showing the oscillating stencil-carrier raised after making the impression. Fig. 7 is a detail side elevation of the gear for turning the ink-reservoir and inking-roller in contact, so as to supply ink to the latter. Fig. 8 is a detail transverse section of the oscillating carrier and pushers on line 8 8, Fig. 2; and Fig. 9 is an exaggerated broken detail section of the ink-reservoir to show its construction more clearly.

Similar letters of reference indicate corresponding parts.

Referring to the drawings, A indicates the frame of my machine, which is provided with

an impression bed or table A', having a raised portion A''. Journaled in suitable bearings of the frame A is a driving-shaft B, which carries a clutch B' and a sprocket-wheel B'' or a pulley, according to whether a sprocket-chain or belt is used to transmit power to it from a suitable source. Arranged on the shaft are cam-disks C C', in a cam-groove C' of which cam-disks C a projection or roller d on an arm D travels, said arm being fixed to a transverse rock-shaft E, journaled in suitable bearings in the frame by means of a hub e, set over the said rock-shaft, and a set-screw e'. This rock-shaft E also supports the oblong frame F, that is provided with a sheet-metal bottom plate F', having two longitudinal parallel slots f, (see Figs. 5 and 8,) through which the pusher operates so as to feed or carry the stencil-cards S along said plate. The frame F is therefore designated the "oscillating stencil-carrier." Above the stencil-carrier, at its rear end, is arranged an upwardly-extending receiving box or hopper G, and above the front or free end of the carrier is arranged an upwardly-extending collecting box or hopper G'. Both of these boxes or hoppers are stationary, the receiving-box G being rigidly fastened to brackets G'', rising from each side of the frame A, and the collecting-box G' being also rigidly fastened to the same brackets G''. The said collecting-box G' is sufficiently elevated above the impression-bed as to permit of the oscillation of the stencil-carrier F. The before-referred-to pusher for the stencil-cards S, which drop one after the other from the receiving-box G, consists of a transverse bar H, arranged under the bottom plate F' of the stencil-carrier, and upwardly-projecting noses h, which are cast on the upper side of said bar and protrude through the slots f in said plate, said noses being beveled at their rear ends at h'. The sides of the noses h are grooved, so as to receive the side walls of the slots f and to be guided and upheld thereby. These pushers are struck at properly-timed intervals by means of tappets C'', projecting from the cam-disks C C'. As the cam-disks revolve the stencil-carrier will be oscillated and the stencil-cards fed along by the pusher. The pusher is retracted by the influence of

- a spring *i*, (see Fig. 2,) coiled around the rock-shaft *E* and inclosed by a loose protecting-sleeve *I*. As shown in dotted lines in said Fig. 2, one end of the spring *i* is anchored in the hub *f'* of the stencil-carrier and the other end in a rotary collar *I'*, confined between the hub *e* of arm *D* and said sleeve *I*, which collar is flexibly connected by a wire, thong, or strap *J* with an eye *h'* of the transverse bar *H* of the pusher. The side bars of the oscillating stencil-carrier are provided, as shown in Fig. 4, at points between the boxes *G G'*, with guide-grooves *f*² for the ends of the stencil-cards *S* as they are pushed along, and which hold the cards in position against the tendency of the noses of the pusher to press them out of place as the latter springs back.
- Pivoted above the bottom plate *F'* of the stencil-carrier is a gravitating dog or detent *f'*, the tooth of which bears upon the stencil-cards, said dog allowing the stencil-cards to travel forward, but not to move back. The cam-disk *C*³ is provided with a suitably-conformed cam-groove, in which travels a pin or roller *k* on a lever *K*, fixed to a transverse rock-shaft *k'* and at its upper end to a transverse pivot-rod *k*², which supports forwardly-extending L-shaped arms *l*, in the outer ends of which is journaled the transverse shaft *L'* of the inking and impression roller *L*, which travels above the bottom plate *F'* of the stencil-carrier. The shaft *L'* passes through and is guided in suitable slots in each side bar of the stencil-carrier, such slots being each composed of a longitudinal lower portion *m*, a parallel raised portion *m'* to the rear thereof, and an inclined connecting portion *m*². The action of the cam *C*³ on the lever *K* causes the pivoted arms *l* to move the shaft *L'* back and forth in the slots, so as to properly actuate and place the inking-collar *L*. The pivotal connection at *k*² is required by reason of the fact that the stencil-carrier oscillates and must raise and lower the inking-roller with it. At one end of the shaft *L'*, Figs. 1 and 2, is fixed a pinion *N*, which is adapted to mesh with the stationary toothed rack *N'*, arranged at one side of the frame upon the table or bed *A'*.
- O* is a bracket or lug fixed to the frame *A* some distance behind the toothed rack *N'*, and to which is pivoted at *p* a movable toothed rack *P*, which is provided at one side with an arched strap or guide-rail *P'*.
- Slides *Q* are guided on the side bars of the stencil-carrier *F* by means of headed studs *q*, projecting from the latter and passing through slots *q'* in said slides. Springs *R*, fixed at one end to the stencil carrier and at the other end to eyes *r* on the slides, draw the latter normally forward into the position shown in Fig. 2. The slides *Q* are provided with bearings *Q'* for the ends of the shaft *T* of the cylindrical ink-reservoir, which consists, as shown in Figs. 2, 4, 5, and 6, of a circular end disk *t*, which is smooth-bored and

is brazed against one end of the enlarged middle portion *t'* of the shaft, and which middle portion is screw-threaded at its opposite end, so as to receive the centrally-screw-threaded closing-disk *t*². Brazed at one end to the fixed end disk *t* is a perforated or reticulated cylinder or cage *T'*, which is of less diameter than the said disk, so as to leave a projecting retaining-flange. The proportion of the closing-disk *t*² relatively to the said cylinder is the same, so that a retaining-flange is also provided.

Referring more particularly to Fig. 9, the cylinder *T'* is tightly wrapped around with a large number of windings or layers *T*², of muslin or the like, through the meshes of which suitable ink in the reservoir exudes. The windings or layers of fabric will be protected by the projecting edges or peripheries of the disks *t* *t*². When the reservoir is to be first filled, the closing-disk *t*² is unscrewed, ink placed in the reservoir, and then the disk *t*² screwed tightly home, so as to hermetically close the reservoir. The reservoir is then placed in a suitable lathe and revolved at an extremely high rate of speed, so that the ink is caused to penetrate through and saturate the windings or layers *T*². After the windings have been saturated in this way the reservoir is mounted in position in the machine, and as the ink is used up it will be fed by capillary attraction. The reservoir is revolved in contact with the inking-roller *L* by means of a pinion *U* on its shaft *T*, which meshes with the oscillating toothed rack *P*, said pinion being caused to mesh with said rack by the action of fixed cam *U'* on the arm *l*, which is adapted to bear on fixed collars *t*³ on the shaft *T*. The end of the shaft *T* travels upon the inner side of the strap or guide-rail *P'*, before referred to.

For the purpose of preventing the congealing of the ink in the reservoir and to masticate or grind up any particles therein a number of grinding-balls *V* are placed in the reservoir. By the rubbing of the balls together a certain degree of heat is generated, which tends to prevent the thickening of the ink, while their abrasive action reduces any sediment or particles in the ink to a fine state, and thus enables the ink to feed, as required, through the fabric layers or windings *T*.

The operation of the machine is as follows: Stencil-cards, in the required order, are placed in the receiving box or hopper *G* and the machine started. The cam *C* causes the stencil-carrier to be oscillated, and after a few oscillations the pusher *H* will have taken the lower cards from the receiving-box and arranged them one after the other along the stencil-carrier. It will be observed that the cards in the receiving-box *G* rest upon the bottom plate of the stencil-carrier and that as the latter oscillates the cards will be shaken down, so that they will feed nicely from said receiving-box. Just before the first card

reaches the outer end of the stencil-carrier and the latter moves down the attendant places an envelop or wrapper on the raised portion A² of the table A', and when the stencil-carrier comes down on it the inking-roller L will be brought out of contact with the ink-reservoir (see Fig. 1 and dotted lines Fig. 5) by the action of the cam C² on the lever K and the latter on the arms l, and the shaft 10 L' of said roller will move down the inclined slot portions m² and into the lower slot portions m, so that the roller is brought in contact with the stencil, a double impression being given by the backward-and-forward movement of said roller, so that a good strong imprint is made on the envelop or wrapper. When the stencil-carrier moves up, beveled spring-catches g on the lower end of the collecting-box G' enter holes f⁴ in the bottom plate F' and catch up the used stencil-card. Between the holes f⁴ the bottom plate F' has a cut-out f⁵ of such size that the impression from the card can be made through it. During the upward movement of the stencil-carrier the fixed cam on the carrier-arms of the inking-roller is brought in contact with the collar l' of the shaft T of the ink-reservoir, so that the slides Q and the ink-reservoir are pushed back, this action causing the movable 25 toothed rack to swing downwardly, as shown in Fig. 7, and the pinion to travel upon and mesh with the said rack, thus rotating the ink-reservoir. At the same time the shaft of the inking-roller has moved up into the upper slot portion m' and the roller is in contact with the fabric-covered inking-surface of the ink-reservoir and is inked by the rotation thereof, as shown in Fig. 5. When the stencil-carrier moves down again, another card is 30 moved in position for printing, and the reservoir is moved back to its forward position by the action of the springs R on the slides Q.

Having thus described my invention, what I claim as new, and desire to secure by Letters 45 Patent, is—

1. In a machine for addressing envelops or wrappers, the combination with an impression bed or table, of an oscillatory stencil-carrier, a stationary receiving-box, means for oscillating said stencil-carrier toward the latter, means for feeding the stencil-cards from said box, along said carrier, and means coöperating with the stencil-cards for producing an impression upon the article placed upon the impression bed or table, substantially as set forth.

2. In a machine for addressing envelops or wrappers, the combination with an impression bed or table, of an oscillatory stencil-carrier, stationary receiving and collecting boxes above the stencil-carrier, means for oscillating said stencil-carrier toward the said boxes, means for feeding the stencil-cards from the receiving-box, along said carrier, and means coöperating with the stencil-cards

for producing an impression upon the article placed upon the impression bed or table, substantially as set forth.

3. In a machine for addressing envelops or wrappers, the combination with an impression bed or table, of a movable stencil-carrier provided with ways along which the stencil-cards are fed, a pusher, means for positively actuating said pusher so as to feed the cards along the carrier, a spring for automatically returning the pusher to normal position, and means coöperating with the stencil-cards for producing an impression upon an envelop or wrapper, substantially as set forth.

4. In a machine for addressing envelops or wrappers, the combination with an impression bed or table, of a movable stencil-carrier provided with ways along which the stencil-cards are fed, a card-push, a rotary shaft, a tappet mounted on said shaft, said tappet striking said pusher, a spring for automatically returning the pusher to normal position, and means coöperating with the stencil-cards, for producing an impression upon an envelop or wrapper, substantially as set forth.

5. In a machine for addressing envelops and wrappers, the combination with an impression bed or table, of a removable stencil-carrier, an ink-reservoir supported on the carrier, an inking-roller, means for guiding the latter from and in contact with the ink-reservoir to printing position, over the said bed or table, and means for feeding the stencil-cards along said carrier, substantially as set forth.

6. In a machine for addressing envelops and wrappers, the combination with an impression bed or table, of an oscillating stencil-carrier, a rotary ink reservoir and distributor, means for rotating the latter during the oscillation of the stencil-carrier, an inking-roll adapted to turn in contact with the said reservoir and distributor, and means for moving the inking-roll along the stencil-carrier to make an imprint through the stencil-cards, substantially as set forth.

7. In a machine for addressing envelops or wrappers, the combination with an impression bed or table, of a movable stencil-carrier, a rotary ink-reservoir having a pad-like circumference for distributing the ink, means for rotating the ink-reservoir during the oscillation of the stencil-carrier, an inking-roller, means for guiding the inking-roller in position for printing and in a higher position for taking ink, and means for moving the inking-roller along the stencil-carrier for performing the two said functions, substantially as set forth.

8. In a machine for addressing envelops or wrappers, the combination with an impression bed or table, of a movable stencil-carrier, a rotary ink reservoir and distributor, gearing connected with the carrier and the shaft of the ink-reservoir, an inking-roller, means

for moving the same along the stencil-carrier and in contact with said reservoir, and gearing for turning said inking-roller so as to cause it to coöperate with the stencil-cards 5 for producing the impression upon the envelopes or wrappers, substantially as set forth.

In testimony that I claim the foregoing as

my invention I have signed my name in presence of two subscribing witnesses.

CHARLES A. BELKNAP.
